UNITED STATES PATENT OFFICE

PERCY C. ROSS, OF COLUMBUS, INDIANA

DESIGN FOR A PICTURE FRAME

Application filed February 13, 1930. Serial No. 34,524. Term of patent 3½ years.

To all whom it may concern:

Be it known that I, Percy C. Ross, a citizen of the United States, residing at Columbus, in the county of Bartholomew and State of Indiana, have invented a new, original, and ornamental Design for a Picture Frame, of which the following is a specification, reference being had to the accompanying drawing, forming part thereof.

I claim:—

The ornamental design for a picture frame as shown.

PERCY C. ROSS.
